UNITED STATES PATENT OFFICE

2,495,658

CARRYING APPARATUS

Harry W. Moseley, Warren, Ohio, assignor to
Republic Steel Corporation, Cleveland, Ohio, a
corporation of New Jersey

Application December 16, 1948, Serial No. 65,579

5 Claims. (Cl. 294—67)

1

This invention relates generally to the article-handling art and particularly to an adjustable carrier for packages of different sizes.

Article carriers, particularly carriers for different sized packages, as constructed heretofore, have possessed certain disadvantages. With many types of packages it is important to be able to lift and carry them with their front vertical surfaces substantially flush with the free ends of the lifting fingers so that the packages may be stacked against other stacks without being rehandled. When such packages differ in size and weight the standard carriers cannot maintain the lifting fingers substantially horizontal with the different sized loads. It is important to maintain the carrying fingers substantially horizontal for if they are inclined the packages thereon are precariously supported. In conventional carriers it is impossible to maintain these fingers horizontal when carrying packages of different sizes and weights except by positioning the packages at different places on the fingers and such positioning is not desired for the reason just stated. As a result, the front faces of some packages carried by conventional carriers may overhang or have their front surfaces flush with the free ends of the fingers while other packages will have those faces located back of the front edges of the fingers and it will require additional operations to stack such packages against another stack after they are removed from the carrier.

The present invention avoids these disadvantages by providing an article carrier whose fingers may be maintained in a horizontal position when the carrier is loaded with articles of different sizes and weights as well as when it is empty, and which may be adjusted for packages of different sizes and weights so that the vertical front faces of each package may be substantially flush with the free ends of the fingers.

The present invention will be better understood by reference to the accompanying drawings in which one modification of the invention is disclosed and in which:

Fig. 1 is a perspective view of an article carrier in unloaded position;

Fig. 2 is a perspective view of the carrier suspended in transporting position while loaded with a package;

Fig. 3 is a side elevational view of the carrier of Figs. 1 and 2 showing the parts thereof in the positions they occupy when maximum and minimum size packages are being carried; and

Fig. 4 is an end elevational view of the apparatus of Fig. 3 taken from the right hand end of the latter.

The carrier of the drawings comprises a new combination of cooperating parts. The guide block 1 carries depending, substantially vertical 60

2

arms 2 from the lower ends of which article-supporting fingers 3 extend substantially horizontally. The guide block 1 is fitted with slides 4 between which a horizontal lifting bar 5 is slidable. This bar 5 is disposed above and substantially parallel to lifting fingers 3, carries a stop pin 6 to engage block 1 and prevent disassembly of the block and arm and at its free end is pivotally connected to a link 7 which at its upper end is pivoted to a hook 8. The hook 8 is engageable with either of two links 9 and 9a extending upwardly from the guide block 1. Link 7 has hand grips 10 on opposite sides thereof for easy manipulation thereof and at its upper end is curved to receive a lifting hook 12 attached to any conventional hoist.

A horizontal shaft 15 is journaled in the free end of lifting bar 5 and is provided with a crank 16 by which it may be rotated. This shaft is provided with threads 17 at its journaled end, and with other threads 18 at the end opposite said crank, which latter threads are opposite hand to threads 17. The threads 17 may be of the same pitch or of a different pitch than threads 18. Threads 18 engage a nut 19 which is fixed in guide block 1.

A back stop has a head 25 provided with an aperture through which bar 5 extends, and a threaded hole to engage with threads 17 of shaft 15, and includes two vertical legs 26 which extend down into or substantially into the space between the parallel lifting fingers 3. These legs may be connected together near their lower ends, as at 27, if desired (see Fig. 1).

From the foregoing description it will be understood that when crank 16 is turned, shaft 15 will be rotated and bar 5 will be moved endwise in guide block 1 by reason of the turning of the screw-threaded part 18 of shaft 15 in the fixed nut 19. In this manner the free end of bar 5 may be moved toward or away from guide block 1. Since threads 17 engage threads in back stop 25, the latter will be moved simultaneously and in the same direction with bar 5 when shaft 15 is rotated. Thus, assuming that the arms 2 are fixed in position, when shaft 15 is rotated bar 5 will be moved toward arms 2 at a certain rate. If back stop 25 were fixed to bar 5 instead of being mounted on shaft 15, back stop 25 would move toward arms 2 at the same time and rate of speed as bar 5. However, since back stop 25 has threaded engagement with threads 17 on shaft 15, back stop 25 is moved toward arms 2 additionally by these threads and hence at a rate faster than the rate of movement of bar 5. Because threads 17 are opposite hand to threads 18, back stop 25 will move faster than bar 5. It follows from this description that by rotating shaft 15, bar 5 may be brought to its extended position as shown in

full lines in Figs. 2 and 3, and that at such time the back stop 25 may also be in its fully extended position. With the parts so positioned, the minimum size package, whose horizontal width is indicated at A in Fig. 3, may be positioned on the carrier with its front surface substantially flush with the free ends of fingers 3, and that when so positioned and the hook 8 is disconnected from links 8 or 8a, and a lifting force is applied to the upper end of link 7, the center of gravity of the carrier and the package thereon will be substantially in vertical alignment and below the center line of the pivotal connection of link 7 to bar 5. Because of this location of the center of gravity, the carrier may be lifted and moved with the package thereon while the fingers 3 are maintained in a substantially horizontal position; and the package may be deposited on the top of a stack of packages with its front vertical face substantially engaging the rear vertical face of a previously made stack of packages, without any re-handling or additional handling of the package.

When the package has been deposited on the stack, the carrier may be lowered until its fingers 3 rest on a support, whereupon link 7 may be pivoted to engage hook 8 with link 8 or 8a. When the carrier is again lifted in empty condition, the fingers will still be maintained substantially horizontal. If a larger package is to be carried, shaft 15 is rotated to move the back stop 25 toward arms 2 far enough for the front face of the package to be substantially flush with the free ends of fingers 3. In that adjustable position, and with link 7 in a vertical position, the center of gravity of the package and carrier will be substantially vertically beneath the pivotal connection of link 7 to bar 5, as previously described. The position of the parts, when a package of the maximum width, indicated by line B on Fig. 3, is to be carried, is indicated in dotted lines in Fig. 3 with the back stop 25 disposed close to arms 2.

It will be understood that the parts may be adjusted in this manner to accommodate packages of all sizes between this maximum and minimum size and in each instance the front face may be flush with the free ends of the fingers and the fingers will be horizontal.

Having thus described the present invention so that those skilled in the art will be able to practice it, I state that what I desire to secure by Letters Patent is defined in what is claimed.

What is claimed is:

1. An article carrier comprising a guide block, a bar having one end slidable in said block, a stop slidable on said bar and depending therefrom, fingers below and substantially parallel to said bar, and means having a threaded shaft

engaging said block, bar and stop for moving said bar and stop toward or away from said block simultaneously but at different rates, and lift-engaging means adjacent the other end of said bar.

2. An article carrier comprising a guide block, a bar having one end slidable endwise in said block, a stop slidable on said bar, carrying means below said bar and connected to said block, a shaft rotatably journaled in said bar, said shaft having threads engaging said stop and other threads engaging a nut fixed in said guide, said threads being of opposite hands, and lift-engaging means near the other end of said bar.

3. An article carrier comprising a guide block, horizontal carrying fingers below and supported by said block, a horizontal lifting bar having one end slidable endwise in said block, a stop slidably surrounding said bar and extending therebelow, a shaft rotatably journaled in said bar and having opposite handed, differential pitch screw-threaded engagement with said back stop and with a nut fixed in said guide, and a lifting link pivoted to the other end of said bar.

4. An article carrier comprising a guide block, a horizontal lifting bar having one end slidable endwise in said block, horizontal carrying fingers below said bar and connected to said block, a vertical stop, a shaft rotatably journaled in said bar and having differential different pitch, opposite handed screw-threaded engagement with said stop and with a nut fixed in said guide, and a link attached to the other end of said bar.

5. An article carrier comprising a guide block, arms depending substantially vertically therefrom, carrying fingers extending horizontally from the lower ends of said arms, a horizontal lifting bar having one end slidable endwise in said guide block above said fingers, a back stop depending vertically from said bar in front of said arms, a shaft rotatably journaled in said bar and having opposite handed screw-threaded engagement with said back stop and with a nut fixed in said guide, the pitch of the shaft threads engaging said nut being less than that of the shaft threads engaging said back stop, a link pivoted to the other end of said bar, a hook pivoted to the upper end of said link and a bale attached to said guide for engagement with said hook.
